CLAIM

The ornamental design for a container lid, as shown and described.

DESCRIPTION

FIG. 1 is a bottom perspective view of a container lid.
FIG. 2 is a bottom perspective view of the container lid.
FIG. 3 is a right bottom perspective view of the container lid.
FIG. 4 is a front view of the container lid.
FIG. 5 is a back view of the container lid.
FIG. 6 is a right side view of the container lid.
FIG. 7 is a left side view of the container lid.
FIG. 8 is a top view of the container lid.
FIG. 9 is a bottom view of the container lid.
FIG. 10 is an exploded view of the container lid of FIG. 1 with a scoop being in a removed position.
FIG. 11 is a front view of the container lid with the scoop in the removed position; and,
FIG. 12 is a right side view of the container lid with the scoop in the removed position.
The features shown in broken lines in the drawings depict environmental subject matter only and form no part of the claimed design.
